LATCH TRIP THERMAL CIRCUIT CONTROLLER
Bert R. Wanlass, Warren, Mich., assignor to General
Motors Corporation, Detroit, Mich., a corporation of
Delaware

Filed Nov. 25, 1960, Ser. No. 71,693
5 Claims. (Cl. 200—116)

This invention relates to a circuit controller and more particularly to a circuit controller including means for maintaining the controller in a closed position for a predetermined period of time and then automatically returning the controller to an open position.

The controller of this invention is particularly useful for the remote control of power actuated members which are movable between open and closed positions. Once the controller is initially closed, it will remain in closed position for a predetermined period of time sufficient to permit the power actuated member to be moved between its open and closed positions and will then automatically open to de-energize the power actuating means. The means for maintaining the controller in a closed position can be overridden at any time desired by the operator so as to provide for movement of the power actuated member to a position intermediate its terminal positions.

In the preferred embodiment of the invention, the controller comprises a double-pole, double-throw switch which includes bi-metallic detent means. The bi-metallic detent means are automatically engageable with the switch actuator upon closure of the switch to hold the actuator in a position to maintain the switch contacts in a closed position until the bi-metallic means has been sufficiently heated so as to move out of engagement with the actuator and allow the actuator to return to neutral position to open the switch.

The primary object of this invention is to provide a new and improved circuit controller. Another object of this invention is to provide a circuit controller which includes means for maintaining the controller in a closed position for a predetermined period of time. A further object of this invention is to provide a new and improved circuit controller which includes means for maintaining the controller in a closed position for a predetermined period of time and for automatically opening the controller upon the expiration of this period of time. Yet another object of this invention is to provide a new and improved double-pole double-throw type switch which includes bi-metallic detent means for maintaining the switch in a closed position once the switch actuator has been initially moved to close the contacts of the switch.

These and other objects of this invention will be readily apparent from the following specification and drawings wherein:

FIGURE 1 is a sectional view of a circuit controller according to this invention, with the controller being shown in open position;

FIGURE 2 is a sectional view taken generally on the plane indicated by line 2—2 of FIGURE 1;

FIGURE 3 is a sectional view taken generally along the plane indicated by line 3—3 of FIGURE 1;

FIGURE 4 is a view similar to FIGURE 1 showing the controller in a closed position; and

FIGURE 5 is a sectional view taken generally along the plane indicated by line 5—5 of FIGURE 1.

Referring now to the drawings, the controller includes a housing 10 of generally rectangular shape and having a pair of laterally extending mounting flanges 12, one at each end thereof. The upper opening 14 of housing 10 is defined by a continuous laterally inwardly extending flange 16 which acts as a locating means for the switch actuator in the open and closed positions thereof, as will be further described. The lower opening 18

2

of housing 10 is closed by a switch base plate 20 of insulating material. Oppositely disposed spring arms 22 mount contact buttons 24 at the free ends thereof, with spring arms 22 being secured to the base 20 by contact rivets 26. A circular spring seat 28 and the base portion of a generally U-shaped bi-metallic detent member 30 are secured to the base plate 20 by a contact rivet 34 which provides the center hot lead for the controller.

The base plate 20 is secured with opening 18 by providing a pair of upwardly extending slots 36, FIGURES 1, 3 and 4 in each side of the housing 10, generally opposite the contacts 24, with slots 36 being apertured at 38, FIGURE 3, to receive the tangs 40 of angular locking members 42 which are received within angle slots 44 provided in the base plate 20 and lateral flanges 46 thereof, the latter fitting within slots 36. Base plate 20 further includes a lateral flange 48 intermediate each pair of flanges 46 which is received within a slot 50 provided in each side wall of the housing 10. Flanges 48 are slotted at 52 to pivotally and slidably receive a pair of laterally extending lugs 54 on an actuator member 56 of insulating material. An actuating button 58 includes a central tapered rivet 60 which is received within a complementary shaped opening in member 56 and secured thereto by heading over the end of the rivet 60 within a shouldered bore 62 of the member 56. Button 58 includes laterally extending flanges 64 at each end thereof which engage the end portions of flange 16 of housing 10 in the open or neutral position of the controller to locate member 56 and button 58 as shown in FIGURE 1, with flanges 64 and the end portions of flange 16 being held in engagement with each other by a coil torsion spring 66 which seats on the spring seat 28 and on the shoulder 68, FIGURE 2, of bore 62.

Member 56 further includes end box sections 70 which open to button 58 and extend from each side of the central portion 71 of the member. A portion 72 of the bottom wall of each box section is cut away to allow passage of the legs 74 of member 30 therethrough. A slot 76 extends through the bottom wall and a portion of the end wall of each box section 70, with each slot including an enlarged circular portion 78 for grippingly receiving a contact button 80. Each button 80 is electrically connected to a leg 74 of the member 30 by means of wires having one end thereof secured to the button and the other end thereof secured to a shouldered portion 82 at the free end of each leg. Buttons 80 are adapted to engage the buttons 24 to close the controller.

When the switch is in an open or neutral position as shown in FIGURE 1, the shouldered portions 82 of the legs 74 of member 30 slidably engage or grip the generally vertically extending walls 84 of the central portion 71 of member 56. When it is desired to close the switch, the operator engages the button 58 so as to depress one end of this button. Assuming that the left-hand end is depressed, the button 58 and member 56 will both pivot and slide as a unit relative to base plate 20 as lugs 54 move within slots 52 and spring 66 is compressed, as shown in FIGURE 4, so that the shouldered portion 82 of the left-hand leg 74 of member 30 will engage over the left-hand upper corner or shoulder of portion 71 of member 56 to thereby maintain the left-hand contacts 80 and 24 in a closed position despite release of the button 58 by the operator. The engagement of the right-hand end flange 64 of button 58 with the right-hand end portion of the flange 16 maintains this end of the button in its position as shown against the action of spring 66. Upon closure of the left-hand contacts 80 and 24, a current path will be completed from the hot lead 34, through the left-hand leg 74 of member 30, and across the contacts 80 and 24 to the left-hand contact 26 by means of the spring arm 22. After a predetermined period of time,

the left-hand leg 74 of the member 30 will be sufficiently heated so that it will shift or bend slightly to the left relative to the base of member 30 so as to move outwardly of the left hand upper corner or shoulder of portion 71 whereupon the spring 66 will instantaneously return the member 56 and button 58 to their position as shown in FIGURE 1 to thereby break the circuit across the contacts 30 and 24 and open the controller.

It will be appreciated that closure of the right-hand set of contacts 30 and 24 will operate in a like manner to maintain the controller in a closed position for a predetermined period of time and then open the controller.

Upon reference to FIGURES 1 and 4 of the drawings, it will be noted that when the button 58 is depressed to close the contacts 30 and 24, the lugs 54 move downwardly within slots 52 and pivot relative thereto against the action of spring 66 so that the actuating button 58 and actuator 56 both pivot and slide as a unit relative to the base 20 until a corner or shoulder of portion 71 moves into engagement with a shouldered portion 82 of one of the legs 74. This is another feature of the subject circuit controller.

Thus, this invention provides a new and improved circuit controller which includes means for maintaining the controller in a closed position for a predetermined period of time and then automatically returning the controller to an open position.

What is claimed is:

1. A circuit controller comprising, in combination, a base member mounting a first contact, an actuator member mounted on said base member for movement between neutral and operating positions with respect thereto, said actuator member including a lower wall provided with an aperture therein and a slot opening to said aperture, a second contact gripped between the edges of said slot and adapted to be closed to said first contact in the operating position of said actuator, means on said actuator member providing a surface terminating in an abrupt shoulder, and a bimetallic member mounted on said base member and electrically connected to said second contact, said bimetallic member projecting through said aperture and including shoulder means normally biased into engagement with said surface in the neutral position of said actuator member and adapted to move along said surface into engagement with said actuator member shoulder when said actuator member is moved to said operating position thereof to maintain said actuating member in said operating position for a predetermined period of time.

2. A circuit controller comprising, in combination, a base member mounting a first contact, an actuator member mounted on said base member for movement between neutral and operating positions with respect thereto, said actuator member including a generally box-like structure having a pair of side walls and a lower wall provided with an aperture therein and a slot opening to said aperture, a second contact gripped between the edges of said slot and adapted to be closed to said first contact in the operating position of said actuator, a bimetallic member mounted on said base member and projecting through said aperture, said bimetallic member being electrically connected to said second contact and including shoulder means normally biased into engagement with one of said side walls in the neutral position of said actuator member, said shoulder means being adapted to move along said one of said side walls and into engagement with the upper edge thereof when said actuator member is moved to said operating position thereof to maintain said actuating member in said operating position for a predetermined period of time.

3. A circuit controller comprising, in combination, a base member mounting spaced first contacts, an actuator member mounted on said base member for movement between neutral and opposite operating positions with respect thereto, said actuator member including a pair of

generally box-like structures, each of said structures including a pair of oppositely disposed side walls and an intermediate lower wall provided with an aperture therein and a slot opening to said aperture, a second contact gripped between the edges of each slot and adapted to be closed to a respective first contact in one of the operating positions of said actuator, a generally U-shaped bimetallic member mounted on said base member, each leg thereof projecting through one of said apertures and being electrically connected to one of said second contacts, shoulder means on each said leg normally slidably engaging one of said side walls in the neutral position of said actuator member, one of said shoulder means moving along a respective one of said side walls into engagement with the upper edge thereof when said actuator member is moved to one of said operating positions thereof to maintain said actuating member in said one of said operating positions for a predetermined period of time.

4. A circuit controller comprising, in combination, a base member mounting spaced first contacts, an actuator member mounted on said base member for movement between neutral and operating positions with respect thereto, spaced second contacts mounted on said actuator member, each adapted to be closed to a respective first contact in the operating position of said actuator member, said actuator member including a central portion having oppositely disposed spaced surfaces, each terminating in an abrupt shoulder, a generally U-shaped bimetallic member having its base portion secured to said base member and enveloping said central portion, each leg of said bimetallic member being electrically connected to one of said second contacts and including shoulder means, each being normally biased into engagement with a respective surface in the neutral position of said actuator member, movement of said actuator member to said operating position thereof moving one of said surfaces relative to a respective one of said legs to move one of said actuator member shoulder means into engagement with a respective one of said bimetallic member shoulder means, each leg of said bimetallic member being in the current path to a respective second contact whereby closure of a pair of said first and second contacts will cause the one leg respective to the closed second contact to be heated and to flex relative to its respective surface after a predetermined period of time to move the one shoulder of said one leg out of engagement with said one actuator member shoulder and allow said actuator member to return to neutral position.

5. A circuit controller comprising, in combination, a base member mounting a first contact, an actuator member mounted on said base member for movement between neutral and operating positions with respect thereto, said actuator member including a box portion having a lower wall provided with an aperture therein, a second contact mounted on said lower wall and adapted to be closed to said first contact in the operating position of said actuator member, said actuator member including a surface terminating in an abrupt shoulder within said box portion, and a bimetallic member mounted on said base member and electrically connected to said second contact, said bimetallic member projecting through said aperture and including shoulder means normally biased into engagement with said surface in the neutral position of said actuator member, movement of said actuator member to said operating position thereof moving said surface relative to said bimetallic shoulder to move said actuator member shoulder into engagement with said bimetallic member shoulder, said bimetallic member being in the current path to said second contact and maintaining said actuator member in said operating position for a predetermined period of time until said bimetallic member becomes heated to an extent to move said shoulder thereof out of engagement with said actuator member shoulder.

and allow said actuator member to return to said neutral position thereof.
